(57) **CLAIM**

The ornamental design for a sliced rectangular block of food material having two longitudinal cuts, as shown and described.

DESCRIPTION

FIG. 1 is a side perspective view of a sliced rectangular block of food material having two longitudinal cuts, showing our new design;

FIG. 2 is an end view thereof; and

FIG. 3 is a right side view thereof, which is similar to a left side view thereof; and,

FIG. 4 is a top side view thereof, which is similar to a bottom side view thereof.
